METHOD OF CUTTING AND APPLYING RING-LINERS TO CAN ENDS.

1,284,953.

Specification of Letters Patent.

Patented Nov. 12, 1918.

Application filed May 28, 1914. Serial No. 841,566.

To all whom it may concern:

Be it known that I, JAMES A. GRAY, a citizen of the United States, residing at the city and county of San Francisco and State of California, have invented certain new and useful Improvements in Methods of Cutting and Applying Ring-Liners to Can Ends, of which the following is a specification.

10 The hereinafter described invention relates to a method of cutting ring liners from fibrous disk blanks and applying the same to the flange of can ends or covers employed for the sealing or closing of metallic can bodies and more especially those commonly termed "sanitary cans," the steps of the method residing in applying a disk blank within the orifice of a conveying member, transporting the blank by the movement of the carrier member to a cutting station, cutting from such blank a central core or disk and leaving a cut ring liner of proper size within the orifice of the carrier, advancing the cut ring liner by the movement of the carrier to a feed station for can ends and positioning an end or cover plate with respect to the orifice containing the said cut ring liner, transferring by the action of the carrier member the said ring liner and can end to assembling means where the can end is moved within the orifice and the cut ring liner applied thereto while the ring is within the orifice of the carrier member, and finally discharging the assembled parts from the said conveying member.

Any suitable form of mechanism may be employed for carrying out the described method of cutting ring liners from fibrous disks and applying the same to can ends or covers, but preference is given to the apparatus disclosed by the accompanying drawings, wherein—

Figure 1 is a front elevation of the apparatus disclosing in general the respective positions of the feed for the disk blanks, the carrier member provided with orifices for receiving the disk blanks, the opposing reciprocating means for cutting a ring liner from a positioned blank, the feed means for delivering can ends in axial alignment with the cut ring liners, the assembling means for applying the cut ring liners to the can ends, and the inter-related mechanism for imparting timed movement to the respective working parts.

Fig. 2 is a vertical sectional side elevation taken on line $x-x$ of Fig. 1 of the drawings, viewed in the direction of the arrows.

Fig. 3 is a perspective view of the carrier member, illustrating the relative position of the feed means for the disk blanks and can ends, the cutting means for cutting a ring liner from the positioned disk blanks, the assembling means for applying the cut ring liner to an aligned can end, and the drive means for the carrier member.

Fig. 4 is a perspective view of one of the fibrous disk blanks.

Fig. 5 is a similar view of a cut ring liner.

Fig. 6 is a similar view of a can end with a liner ring applied thereto.

In the drawings—the numeral 1 is used to designate any suitable form of a supporting frame capable of sustaining the working parts of the apparatus, and within which frame is secured a stationary supporting table or disk 2; through a bearing 3 depending therefrom extends a vertically disposed driven shaft 4. To the upper end of this vertical shaft is keyed or otherwise secured a horizontally disposed turret or carrier member 5, which is held a slight distance above the stationary table member 85.

2. An intermittent or step rotation is imparted to the centrally disposed shaft 4 and the horizontally disposed turret or carrier member 5 by any suitably driven mechanism, preferably by means of a multilated worm 6 on a horizontally disposed shaft 7 meshing with a worm gear 8 secured to the lower end of the said vertically disposed shaft 4—Figs. 1, 2 and 3 of the drawings, the said shaft 7 working in suitable bearings 95 located in the base portion of the frame structure 1.

From the sides of the machine frame and in substantial alignment with the upper face of the stationary platform 2 and the upper face of the turret or carrier 5 respectively, project the brackets 9 and 10, which support respectively the holder 11 adapted to hold a stack of can ends 13 and the holder 12 adapted to hold a stack of disk blanks 14. 105 The disk blanks 14 are successively delivered from the holder 12 into one of the circumferentially disposed vertical openings or orifices 15 of the turret or carrier 5 and onto the circumferentially disposed seat 110 or shoulder 16 of the said opening for receiving and supporting the said disk blank,

the said blanks being guided into the positioned opening 15 of the turret or carrier member 5 by means of the lateral guide-ways 15' formed in the upper face of the 5 said turret or carrier member and which communicate with each of the said openings. The can ends 13 to be lined are successively removed from the holder 11 and positioned onto the stationary platform 2 10 immediately beneath a positioned opening 15 of the turret or carrier 5 by a reciprocating slide plate or blade 43', the said can end as fed onto the said table or platform 2 moving within one of the series of lateral 15 guide cut outs 18' formed in the under face of the turret or carrier 5 and which communicate respectively with the circumferentially disposed vertical openings 15 thereof, so that the vertical wall of the flange of the 20 can end 13 will be embraced thereby and held against displacement.

In the present case, rotary motion is imparted to the shaft 7 from the drive shaft 17, working in bearings 12 secured to the exterior 25 tension side pieces 13 of the frame structure 1. The said drive shaft 17 is driven by a power belt (not shown) working over a belt pulley 18' secured to one end of the said shaft, and the rotation of the drive shaft 17 30 is transmitted to the shaft 7 through the medium of the vertically disposed shaft 18. This shaft 18 has secured to its upper and lower ends respectively the pinions 19 and 19', which mesh with the pinions 20 and 20' 35 secured respectively to one end of the shafts 17 and 7, so that the rotary movement of the shaft 17 is transmitted to the shaft 7.

To a crank 21 on the drive shaft 17 is connected through a pitman 22, a vertically reciprocating cross head 22', Fig. 1 of the drawings. This cross head carries at its lower end a ring die punch 23, which said die punch 23 is of a diameter equal to the interior diameter of the ring liner 14' to be 40 cut from a disk-blank 14, and the said punch is in vertical alinement with a ring die 24 secured to a hollow reciprocating cross-head 24', which said cross-head is connected by a pitman 25 to a crank 25' on the shaft 7, the 45 timed movements of the cranks 21 and 25' of the shaft 17 and 7 respectively being such that the ring die punch 23 and the opposing die ring 24 are moved toward and from each other simultaneously, and together pass from 50 opposite faces into and part way through one of the positioned openings or orifices 15 of the rotatable turret or carrier member 5.

On the inward stroke of the ring die punch 23 and the die ring 24, a liner ring 60 14' is cut from a disk blank 14 seated in the orifice 15, the cut core piece moving into the hollow cross-head 24' and the cut ring liner 14' being left seated on the interior shoulder 16 of the orifice 15.

On the die punch 23 and the ring die 24

moving out of the opening 15, a step rotation is imparted to the horizontally rotatable turret or carrier member 5 to place the said orifice opening 15 thereof with the cut ring liner 14' therein in vertical alinement with reciprocating assembling means for placing the cut ring liner onto the flange 47 of a cam end or cover plate 13. This step or intermittent rotation of the said turret or carrier member is accomplished by the part rotation 70 imparted to the vertical shaft 4 through the medium of the hereinbefore described worm gear 8 thereon, meshing with the mutilated worm gear 6 on the driven cross shaft 7, the step rotation so imparted to the turret or 80 carrier member 5 being such as to place the opening 15 with the cut ring liner therein in alinement with a vertical opening 27 in the stationary table 2, and in alinement with the vertically reciprocating assembling means 85 for placing the cut ring liner 14' onto the flange 47 of a positioned can end or cover plate 13, the assembling means comprising opposing vertically reciprocating plungers 28 and 28', which plungers are movable into 90 and out of the opening 15 of the horizontally rotatable turret or carrier member 5 containing the ring liner 14' to be applied. The plunger 28 forces the cut ring liner from its shouldered seat 16 of the opening or orifice 95 15 onto the flange 47 of the positioned can end 13, the stem 29 of such plunger working through a guide 29', and being connected at its upper end to a lever 30 fulcrumed to a bracket 30' and which carries at its inner 100 end a roll 31 working within an irregular groove 32, cut in one face of a cam 33 secured to the drive shaft 17, so that during the rotary motion of the said shaft reciprocating motion is imparted through the medium of the lever 30 and the stem 29 to the plunger 28.

The companion plunger 28' lifts the can end 13 from its seat into the opening 15 and holds the same in axial alinement with the cut ring liner 14' while the same is forced onto the flange 47 thereof, the stem 28' being connected at its lower end to the outer end of a fulcrumed lever 33'. At its inner end the said lever carries a roll 34 which works 110 within an irregular shaped groove 34' formed in one face of the cam 33 secured to the driven shaft 7. By such form of connection the rotary motion of the shaft 7 is transmitted for imparting vertical reciprocating motion to the plunger 28'.

The plunger 28' works through a vertical opening in the fixed table 2 and on its upward movement or stroke lifts the positioned can end 13 into the alined vertical orifice 125 or opening 15 of the horizontally rotatable turret or carrier member 5 until it reaches a position therein immediately beneath the supporting shoulder, shield or ledge 16 on which rests the positioned cut ring liner 14'. 130

During the upward movement of the plunger 28, the opposing plunger 28 is descending, so that by the time the can end 13 has been lifted into proper position within the opening 15 of the carrier member 5, the plunger 28 is acting on the cut ring liner 14' to force the same from its circumferential seat 16 onto the flange d of the can end 13.

The lined can ends 13 are discharged 10 through a cut out section of the stationary table or platform 2 and conveyed by any suitable means to a place of deposit.

The disk blanks 14 are successively delivered to the rotatable turret or carrier member 5 from a stack of such disks contained within the holder 12 situated at one side of the machine, while the can ends 13 to be lined are delivered onto the table 2 and within the sphere of a properly positioned orifice 15 of the said turret or carrier 5 from a stack of such ends contained within a holder 11 situated at the opposite side of the machine. The disk blanks 14 are successively delivered into a properly positioned orifice 20 15 of the turret or carrier 5 when at rest with its guide-way 15' in line with the lowermost disk of the stack contained within the holder 12, by means of the reciprocating holder 11 slide 36, which works within a guide-way 25 of the bracket 10. During the inward stroke of the feed slide the shouldered end portion 36' thereof engages with the edge of the lowermost disk 14 of the stack of disk blanks and forces the same inwardly through 30 the guide-way 15' into the positioned orifice or opening 15 of the turret or carrier 5.

Reciprocating timed movement is imparted to the feed slide 36 by means of a lever 37 fulcrumed to a bracket 38 projecting from the frame of the machine. The fulcrumed lever 37 is connected by a link rod 39 to an operating lever 39' fulcrumed to a bracket 39^a secured to the opposite side of the machine from bracket 38. At its lower end this lever 39' carries a roll 40 which works within an irregular groove 40' of a cam 41 secured to one end of the drive shaft 7. The rotary motion of the said shaft is thus transmitted for imparting reciprocating motion to the feed slide 36 and to the feed slide 42, to a depending extension 42' of which slide 42 the upper end of the fulcrumed lever 39' is connected by a short link 43, and to the upper 50 face thereof is attached a feed blade 43' which blade on the inward movement of the slide 42 engages with the flanged edge of the lowermost can end 13 of the stack of ends contained within the holder 11 and moves the same therefrom onto the table or platform 2 to a position immediately beneath and in alignment with the positioned orifice or opening 15 of the turret or carrier member 5, the can end as forced inwardly moving within the guide cut out 13'

in the under face of the said turret or carrier member leading to the positioned opening 15, the circumferential flange of the can end when so positioned being partly embraced by the wall of such guide cut out.

70

For the removal of the lowermost end of the stack of can ends 13 within the holder 11 and which end rests on the bracket 9, it is required that the entire stack of ends with the exception of the lowermost or bottom one thereof be raised a slight distance, and for this purpose a pair of spaced spring held cut out arms 44 are fulcrumed to the upper face of the bracket 9. These arms are forced together for a lifting of the stack of ends, by means of the inclines 44' on the longitudinally reciprocating feed blade 43' during the inward movement of the slide 42 acting against the rolls 45 depending from the inner end portion of each fulcrumed arm 44 and by so doing swinging outward or separating such outer end portion of the arms and forcing together or closing the inner end portions thereof, and causing the same to enter between the lowermost two 85 ends of the stack of ends contained within the holder 11 and raise the entire stack with the exception of the lowermost one thereof. With the continued inward movement of the blade 43', the cut out or released 90 can end is removed from within the holder 11 and moved onto the table or platform 2 into a position immediately beneath the positioned orifice or opening 15 of the turret or carrier member 5. On the outward movement of the blade 43' the laterally swinging arms 44 remain in their closed position until the inclines 44' of the said slide are carried beyond the rolls 45, when the tension of the spring 46 draws together the outer 100 end portions of the laterally swinging arms, separating the inner portions and withdrawing the same from beneath the stack of can ends and by so doing lowering the said stack within the holder to position the bottom one thereof for removal on the next inward stroke of the blade 43'.

100

The action of the respective co-operating mechanism of the machine for carrying out the method is such that a disk blank is first fed from a stack of blanks within the holder 12 into a positioned vertical opening or orifice of the horizontally rotatable turret or carrier member 5, and a step rotation then imparted to the said carrier member to place the orifice with its disk blank positioned therein in alignment with the cutting means situated at the cutting station A. Reciprocating motion is then imparted to the opposing co-acting cutting plunger for the cutting of a central core piece from the blank and leaving a cut ring liner on the seat 16 of the orifice or opening 15 of the turret or carrier member 5. The said carrier member with the positioned cut ring liner is then ad- 115 120 125 130

vanced by a step or intermittent rotation until the orifice containing the ring liner is in longitudinal alinement with the feed mechanism for the can end, when the lower-
5 most end 13 from a stack of ends contained within the holder 11 is fed onto the stationary table or platform and placed into axial alinement with the orifice 15 containing the cut ring liner, the flange of the end at such
10 time being partly embraced by the wall of the cut out portion in the under face of the turret or carrier member leading to said orifice. The turret or carrier member with the properly positioned cut liner ring and
15 can end is then advanced to the assembling station B to place the positioned cut ring liner and can end in vertical alinement with the assembling means, motion being im-
10 parted to means at such time to assemble
20 the ring liner and the can end by moving the same relatively axially toward each other while the ring is within the orifice. There-
25 after, the assembling means separate and the turret or carrier member moves the lined can end over the surface of the table or platform 2 toward the discharge outlet thereof, where the same is discharged and conveyed toward a suitable place of deposit.
Having thus described the invention what
30 is claimed as new and desired to be protected by Letters Patent is:—
1. The method of cutting and applying ring liners to flanged can ends, which consists in successively transporting disk
35 blanks of lining material step by step in a substantially horizontal plane; cutting ring liners from the peripheral portions of the successive blanks at an interval between two of such steps; forcing the central parts or
40 wastes of said disks down through and from the ring liners; successively moving can ends, with their flanges which are to be lined projecting upward, in a lower substan-
45 tially horizontal plane and bringing them to rest in line beneath the said ring liners as they successively pause at a subsequent interval between two of such steps; and forcing down the successive ring liners along the interior walls of the flanges of their respec-
50 tive can ends at a subsequent interval between two of such steps.
2. The method of cutting and applying ring liners to flanged can ends, which consists in successively transporting disk blanks
55 of lining material step by step in a substantially horizontal plane; cutting ring liners from the peripheral portions of the successive blanks at an interval between two of such steps; forcing the central parts or
60 wastes of said disks down through and from the ring liners; successively moving can ends, with their flanges which are to be lined projecting upward, in a lower substan-
65 tially horizontal plane and bringing them to rest in line beneath the said ring liners as they

successively pause at a subsequent interval between two of such steps; transporting both the ring liners and the can ends and maintaining their said relation the latter in line beneath the former; and forcing down 70 the successive ring liners along the interior walls of the flanges of their respective can ends at a subsequent interval between two of such steps.

3. The method of cutting and applying 75 ring liners to flanged can ends, which consists in successively transporting disk blanks of lining material step by step in a substan-
80 tially horizontal plane; cutting ring liners from the peripheral portions of the successive blanks at an interval between two of such steps; forcing the central parts or
85 wastes of said disks down through and from the ring liners; successively moving can ends, with their flanges which are to be lined projecting upward, in a lower substan-
90 tially horizontal plane and bringing them to rest in line beneath the said ring liners as they successively pause at a subsequent interval between two of such steps; transporting both the ring liners and the can ends and maintaining their said relation the latter in line beneath the former, with the transport-
95 ing medium interposed between them; and forcing down the successive ring liners 95 through the transporting medium and along the interior walls of the flanges of their respective can ends at a subsequent interval between two of such steps.

4. The method of preparing the flanges of 100 can ends to be subsequently attached to can bodies by means of an interfolded joint or seam to form a hermetic seal, consisting in successively positioning cut can end flange liners in spaced relation; conveying the 105 liners successively in said spaced relation to each other in the plane occupied by the liners; and at the same time maintaining control of and the shape of said liners circularly successively alining the said cut 110 liners with positioned can ends; and uniting the liners and can ends by movement at sub-
115 stantially right angles to the plane of con-
veying.

5. The method of cutting and applying 115 ring liners to the flanges of can ends to be subsequently attached to can bodies by means of an interfolded joint or seam to form a hermetic seal, which consists in suc-
120 cessively cutting and positioning ring liners from flat material, and at the same time pro-
125 ducing central core pieces; removing the central core pieces; conveying the ring liners in flat condition and spaced relation to each other in a plane substantially at right angles to the direction of cutting; and at the same time maintaining control of and the shape of said liners exteriorly; successively alining the said ring liners and can ends; and uniting the ring liners and can 130

ends by movement at substantially right angles to the plane of conveying.

6. A method of forming flat fibrous flexible can end liners from flat liner material and placing them on the annular flat seats of the flanges of shouldered and flanged can ends; consisting in moving flat, flexible, fibrous material along a predetermined path between liner forming members, causing relative movement between said forming members whereby they are brought into contact with said flat fibrous liner material and form therefrom flat annular liners; holding said liners in an orificed member after formation whereby said formed liners are mechanically controlled; moving said orificed member to carry said liners away from said place of cutting and aline them with shouldered and flanged can ends, and causing the said alined can ends and liners to have relative movement whereby the flat fibrous liners are caused to pass around the shoulders of and lie in a flat position on the flanges of said can ends.
7. A method of forming flat fibrous flexible can end liners from flat liner material and placing them on the annular flat seats of the flanges of shouldered and flanged can ends; consisting in intermittently moving flat, flexible fibrous liner material along a predetermined path between liner forming members, causing relative movement between said forming members whereby they are brought into contact with said flat fibrous liner material while said material is stationary, and form therefrom flat annular liners, leaving said liners in an orificed member as formed whereby said liners are mechanically controlled; moving said orificed member to carry said liners away from said place of forming in the same plane in which they were formed, and alining them with shouldered and flanged can ends, and causing the said alined can ends and liners to have relative movement whereby the flat fibrous liners are caused to pass around the shoulders of and lie in a flat position on the flanges of said can ends.
8. A method of forming flat fibrous flexible can end liners from flat liner material and placing them on the annular flat seats of the flanges of shouldered and flanged can ends; consisting in intermittently moving flat, flexible, fibrous liner material along a fixed path between liner cutting or forming members, causing relative movement between said forming members whereby they are brought into contact with said fibrous liner material while said material is stationary, and form therefrom flat annular liners, leaving said liners in an orificed member as formed whereby said liners are mechanically controlled; moving said orificed member to carry said liners away from said place of forming in the same plane in which they were formed, and alining them with shouldered and flanged can ends, and causing the said alined can ends and liners to have relative movement whereby the flat fibrous liners are caused to pass around the shoulders of and lie in a flat position on the flanges of said can ends.

9. A method of forming flat fibrous flexible can end liners from flat liner material and placing them on the annular flat seats of the flanges of shouldered and flanged can ends; consisting in moving flat, flexible, fibrous material along a predetermined path between liner forming members, causing relative movement between said forming members whereby they are brought into contact with said flat fibrous liner material and form therefrom flat annular liners; holding said liners in an orificed member after formation whereby said formed liners are mechanically controlled; moving said orificed member to carry said liners away from said place of cutting and aline them with shouldered and flanged can ends, and causing the said alined can ends and liners to have relative movement whereby the flat fibrous liners are caused to pass around the shoulders of and lie in a flat position on the flanges of said can ends.

10. A method of forming flat fibrous flexible can end liners from flat liner material and placing them on the annular flat seats of the flanges of shouldered and flanged can ends; consisting in intermittently moving flat, flexible, fibrous liner material along a fixed path between liner cutting or forming members, causing relative movement between said forming members whereby they are brought into contact with said fibrous liner material while said material is stationary, and form therefrom flat annular liners, leaving said liners in an orificed member as formed whereby said liners are mechanically controlled; moving said orificed member to carry said liners away from said place of forming in the same plane in which they were formed, and alining them with shouldered and flanged can ends, and causing the said alined can ends and liners to have relative movement whereby the flat fibrous liners are caused to pass around the shoulders of and lie in a flat position on the flanges of said can ends.

11. A method of forming flat fibrous flexible can end liners from flat liner material and placing them on the annular flat seats of the flanges of shouldered and flanged can ends; consisting in moving flat, flexible, fibrous liner material along a predetermined path between liner forming members, causing relative movement between said forming members whereby they are brought into contact with said flat fibrous liner material and form therefrom flat annular liners, leaving said liners in an orificed member as formed whereby said liners are mechanically controlled; moving said orificed member to carry said liners away from said place of cutting and aline them with shouldered and flanged can ends, and causing the said alined can ends and liners to have relative movement whereby the flat fibrous liners are caused to pass around the shoulders of and lie in a flat position on the flanges of said can ends.

In testimony whereof I have signed my name to this specification in the presence of two subscribing witnesses.
